United States Patent

Des. 241,323
Patented Sept. 7, 1976

241,323

SECURITY CONSOLE

Walton E. Sparks, Lexington, and Richard K. Weiss,
Mansfield, Ohio, assignors to Westinghouse Electric
Corp., Pittsburgh, Pa.

Filed Apr. 29, 1975, Ser. No. 572,812

Term of patent 14 years

Int. Cl. D10—05

U.S. Cl. D10—106

FIG. 2

FIG. 1

FIG. 3

FIG. 1 is a front elevational view of a security console showing our new design;

FIG. 2 is a top plan view thereof; and

FIG. 3 is a perspective view thereof.

The perforations are partially shown in FIG. 1 for convenience of illustration, it being understood that the perforations are uniformly continuous over the area indicated.

The rear is flat and unornamented.

We claim:

The ornamental design for a security console, as shown and described.
